UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,118.

Specification of Letters Patent.

Patented Aug. 9, 1921.

Application filed January 16, 1920. Serial No. 351,789.

To all whom it may concern:

Be it known that I, FRED S. CARR, a citizen of the United States, and a resident of Newton, in the county of Middlesex, Commonwealth of Massachusetts, have invented an Improvement in Separable Fasteners, of which the following description, in connection with the accompanying drawings, is a specification, like characters on the drawings 10 representing like parts.

This invention pertains to improvements in separable fasteners, and more particularly to the securing of separable fasteners to fabrics without sewing.

15 In the drawings in which I have shown a preferred embodiment of one form of my invention:

Figure 1 is an elevation of two pieces of fabric secured together by a preferred form 20 of fastener;

Fig. 2 is a section on the line 2—2 of Fig. 1;

Fig. 3 is a side elevation of a preferred form of socket casing prior to attachment 25 thereof to the fabric; and

Fig. 4 is a plan view of the socket shown in Fig. 3.

Referring to the drawings of the preferred form of my invention selected for 30 illustrative purposes, I have shown a separable fastener including a stud 5 secured to the fabric by stud-securing means 6 similar to that shown in my copending application filed herewith, Serial No. 351,780. I have 35 shown a socket including a spring-containing casing 7 containing a spring 8 and secured to the socket-carrying fabric 9 by socket-attaching means 10, which preferably as shown takes the form of a flanged-over disk 40 providing a recess into which the fabric 9

may be crowded by expandible means 11, which preferably forms a part of the socket casing 7.

The stud is secured to its fabric as shown in my co-pending application. The socket 45 may be secured to its fabric 9 by pressing the socket casing in the form shown in Fig. 3 against the fabric 9, while the socket-securing element 10 is held on the opposite side of the fabric, the fabric being pressed 50 into the socket-securing element and the expandible flanges 11 of the socket casing expanding to press the fabric beneath the lip of the part 10.

It will be understood that I use the word 55 "fabric" in its broader sense to include not only woven materials, but any flexible carrying medium.

While I have shown and described a preferred form of one embodiment of my invention, it will be understood that changes involving omission, substitution, alteration and reversal of parts, and even changes in the mode of operation, may be made without departing from the scope of my invention, which is best defined in the following 60 claim.

Claim:

A socket for separable fasteners comprising, in combination, a casing having a relatively large face portion and a stud-receiving aperture therein, a rim for said face portion provided with expandible lip means, a casing-securing part having a flanged-over rim, said 70 lip means expanded to interlock with the 75 flanged-over rim of the casing-securing part.

In testimony whereof, I have signed my name to this specification.

FRED S. CARR.
